UNITED STATES PATENT OFFICE

FRITZ LUBBERGER, OF BERLIN, GERMANY, ASSIGNOR TO SIEMENS & HALSKE AKTIEN-
GESELLSCHAFT, OF WERNERWERK, SIEMENSSTADT, NEAR BERLIN, GERMANY

TELEPHONE SYSTEM

Application filed April 9, 1926, Serial No. 100,803, and in Germany May 27, 1925. Renewed May 11, 1929.

The invention relates to a circuit arrangement for automatic telephone system with impulse storers, and its particular object is to reduce to a minimum, consistent with reliable working, the number of impulse storers required for building up speech connections in a telephone installation.

Systems are known in which all the number impulse receivers for a speech connection are not positioned in conjunction with an impulse storer, and in which one or more of the trains of impulses transmitted by the calling party directly operate the number impulse receivers. If the number impulse receivers, which are to be directly operated, be located at the initial stages of the speech connection, in the known arrangements the connecting up of the impulse storer is effected beyond these number impulse receivers. According to the invention, the quantity of impulse storers is reduced by connecting them up at a point located in front of the number impulse receivers that are directly operated. According to the invention switching means are provided, whereby the impulse receiving devices of a storer cannot be operated until the trains of impulses transmitted by the calling party have operated the number impulse receivers which are to be directly operated.

30 The impulse for connecting up an idle impulse storer can be given as soon as the connecting up point has been taken into use. But alternatively according to the invention it can also be given when the calling party transmits the particular train of impulses which precedes the first train of impulses that operate the storer. The latter arrangement effects a greater reduction of the quantity of impulse storers, because no impulse storer 35 is withdrawn from the general traffic during the time between the taking into use of the junction point and the functioning of the last train of impulses that directly operates a number impulse receiver.

40 According to the invention, the installation is further simplified and cheapened because the impulse receiving relays, which bring about the direct positioning of the number impulse receivers, also effect the positioning 45 of the impulse receiving devices of the storer.

The invention is illustrated in the accompanying drawings comprising Figs. 1, 2, and 3, in which the apparatus used is shown by means of the usual schematic circuit diagrams.

55 Figs. 1 and 2 show by way of example, one method of carrying out the invention, based on a system using Strowger switches. The first group selector IGW (shown in Fig. 1) is accessible in the banks of the preselector 60 H1VW and is positioned by interrupting the loop at the subscriber's station, while the switches in the succeeding stages are controlled by the impulse storer (shown in Fig. 2) by means of earth impulses over the a 65 lead and the application of battery to the b lead.

Fig. 3 shows a modified part of the circuit given in Fig. 1 which enables the impulse for connecting up an idle impulse storer to be 70 combined with the commencement of the first train of impulses.

Let the subscriber's number have five digits. The first train of impulses positions the first group selector, while the succeeding trains of 75 impulses are first of all stored and are then transmitted to the succeeding switches after being translated if necessary.

The first group selector IGW has lifting and rotary motion. The second preselector 80 H1VW is of known construction. DD indicates a sender selector, which here is permanently associated with the first group selector. It forms a rotary switch with 25 positions and is of the known type of step-by-step rotary switch. The impulse sender Z is of known type; its wipers rotate over the six discs A 1-A 6 when they are coupled to a continuously rotating shaft, which is not shown, this being effected when a coupling magnet K is operated. SP (sp 1-4) indicates the storers, which comprise ten-point rotary stepping switches. As the invention does not concern the known devices, but deals with the relationships mentioned in the 85 preamble, the switching devices, required for returning the storers to their normal position are not shown. ST indicates the side switch for the storer, which likewise is constructed after the principle of the rotary step- 90

by-step switch. The arrangements for moving on these switches to their normal position after the release are known and are therefore not shown. The circuit changes forming part of the invention can be followed on the drawing.

Seizure of the first group selector

When the second preselector is positioned, 10 the relay C is operated in the following circuit: earth at the second preselector, c lead, contact 1 m, relay C, contact 2 n, battery, earth. At its contact 3 c it prepares the test circuit of the first group selector, and closes at 15 the contact 4 c the circuit for moving on the sender selector DD as follows: earth, contact 4 c, contact 5 f, contact 6 pd, motor magnet Dd, contact 7 dd, battery, earth.

Positioning the sender selector

20 The sender selector DD rotates until the test relay Pd, is operated in the following circuit: earth, contact 8 f, relay Pd, wiper of the sender selector dd 1, release magnet 25 MS, battery, earth. At its contact 9 pd, the relay PD prepares the circuit of the relay G and marks the selected impulse sender Z engaged by short circuiting its own high resistance winding at the contact 10 pd. 30 When the release magnet MS is deenergized, it causes the side switch ST to return to its home position in some known manner, which is not shown here.

Positioning the first group selector

35 After the first group selector has been taken into use by the second preselector, the relays A and B are operated over the subscriber's instrument. The relay A at its contact 11 a energizes the slow acting relay V over earth, 40 contact 11 a, slow acting relay V, battery, earth, and at the contact 12 v prepares the circuit of the relays U and I. The relay A is deenergized each time the loop is opened at 45 the number dial (for example when dialling the number 3), and at the contact 14 a the following circuit is closed: earth, contact 14 a, contact 12 v, slow acting relay U, relay I, battery, earth. The relay I pulsates and at 50 each impulse closes the circuit of the lifting magnet H over earth, contact 15 i, contact 16 w, lifting magnet H, battery, earth. The group selector raises its wipers in accordance with the impulses transmitted. The slow 55 acting relay U is operated at the first lifting impulse and holds itself operated during the impulse transmission. At the end of the impulses relay U falls back and closes the circuit of the rotary magnet as follows: earth, battery, rotary magnet D, contact 17 d, contact 60 18 v, contact 19 u, contact 20 p, contact 21 k, earth, this circuit having been previously prepared at the contacts 18 v and 21 k. The group selector rotates until the test relay P is 65 operated in the test circuit: earth, contact 3

c, relay P, test lead c'', earth at the second group selector (not shown). It then opens the circuit of the rotary magnet at the contact 20 p and at the same time short circuits its high resistance winding at the contact 22 p, thereby preventing the second group selector being taken into use for another call. The contacts 23 p and 24 p switch through the speaking leads, and the contact 25 p prepares the circuit for positioning the storers. During the positioning of the first group selector, the sender selector has in a reliable manner found an idle impulse sender.

Positioning the storers

70 During the second impulse train, for example, when dialling the number 3, the relay I pulsates in the known manner, and at the contact 26 i, it closes the positioning circuit for the storer Sp 1 over: earth, contact 26 i, contact 25 p, sender selector wiper dd 3, slow acting relay Q, rotary magnet DSp 1, battery, earth. The wiper sp 1 is brought onto the third contact. Relay Q is operated by the first impulse and energizes the side switch magnet ST in the following circuit: earth, contact 56 q, magnet ST, battery, earth. At the end of the train of impulses the relay Q falls back and opens this circuit, the side switch then moves into the position 2. The further trains of impulses (third to fifth) in succession position the wipers sp 2-sp 4 according to the selected numbers such as "5", "7", "9". After the fifth train of impulses, the side switch reaches the position 5. The opening of the rotary off normal shaft contacts 16 w prevents these trains of impulses affecting the lifting magnet H.

Translation

75 In this example the subscriber has dialled the number "33579". But the switches, instead of being positioned according to this number, are to be positioned according to the number "349579". This renders it necessary for the storer to effect a translation, this being done with the assistance of the intermediate distributor ZV. This distributor has the soldering tab zv 11 permanently earthed, the other tabs being connected to corresponding contacts on the storers. The intermediate distributor has its second row of soldering tabs connected to the corresponding terminals in the contact rows I, II, III, IV, V of the disc A 3 of the impulse sender. The disc A 3 has a special contact VI in front of the first contact row I which is connected to a key Ta at the intermediate distributor. In the present case this key is not closed. The tab zv 11 is connected by a jumper wire to the fourth soldering tab in the row I. The soldering tabs in the row II have the jumper wires irregularly connected in accordance with the translation to be effected; for example, in the present 80 110 115 120 125 130

case the storer contact 3 is connected to the impulse sender contact 9. The other rows of soldering tabs are connected to the corresponding contacts. If, however, a translation is also required here, the jumper wires would have to be irregularly connected.

The impulse sender

The impulse sender that is here shown has 10 6 discs A 1 to A 6. The disc A 1 comprises an earthed ring, which is open at the point where the wiper is in its normal position. The disc A 2 has 5 segments I-V. In its normal position the wiper A 2 touches the 15 segment I. The gaps between the segments are so large that the switches can effect the non-numerical selection while the wipers of the impulse sender are moving over the gaps. The disc A 3 has 5 rows of contacts. The 20 gaps between these rows are as large as those between the segments on the disc A 2. In front of the first contact row on the disc A 3 there is the contact VI, which, as stated above, is connected to the key Ta. Its purpose will be explained hereafter. The disc 25 A 4 is divided into 5 segments, which are connected to battery over a resistance W 2, and have gaps of the same size as the discs A 2 and A 3. The disc A 5 comprises 5 30 earthed segments, each of which has a row of 10 contacts wiped over by the brush A 5. This brush only touches the contacts, so that each time another contact is reached, the outgoing a lead is earthed. The gaps between 35 the contacts interrupt the earth, thus creating the current impulses. The sub-division on the disc A 6 is such that the segments I and II and also IV and V, corresponding to the other discs, are interconnected, so that 40 there are altogether 3 gaps, which are so small that they can be bridged by the wiper A 6. The wiper A 6 moves from the segments I-II and III to the succeeding segment before the other wipers A 2 to A 5 45 reach their segments III and IV. The arrangement is required for the operations to be described later on to deal with irregularities in operating the number dial.

It will be assumed that the sender is arranged to start up after the storer has been positioned and that the subscriber has positioned the storers sp 3 and sp 4 while the impulse sender is moving over the segments I-II. After the storer sp 2 has been positioned, 50 the side switch ST moves into its third position in the manner described above. In the position 3 the starting relay An 3 is energized over the side switch arm St 2 in the circuit: earth, side switch arm st 2, position 55 3, relay An 3, battery, earth. Relay An 3 connects up the coupling magnet K over: earth, battery, coupling magnet K, wiper A 6 of the impulse sender, segment "I, II", contact 27 an 3, earth. The magnet K causes the 60 impulse sender to move in the direction of the 65 arrow. The wiper A 1 moves over the earthed disc and closes the following circuits: earth, battery, relay Td, sender selector arm dd 2, wiper A 1, earth; and earth, battery, relay An 3, winding II, contact 28 an 3, wiper A 1, earth. The relay Td is operated in the first 70 mentioned circuit, and at its contacts 29 td and 30 td it connects the impulse sender to the speaking leads, while at its contact 31 td it energizes the slow acting relay G over: 75 earth, battery, slow acting relay G, contact 31 td , contact 9 pd , earth. In the second circuit the relay An 3 locks itself for a complete rotation of the impulse sender. The movement of the wiper A 3 of the sender over the 80 contact VI is without effect. The wiper A 4 moves onto the segment I and thereby applies steering battery to the b'' lead over earth, battery, resistance W 2, segment I, wiper A 4, sender selector arm dd 4, contact 29 td , contact 85 24 p , b'' lead. The wiper A 5 moves over the contacts and at each contact it sends a positive impulse over the a'' lead as follows: earth, contact 32 r , disc contacts for A 5, wiper A 5, sender selector arm dd 5, contact 90 30 td , contact 23 p , lead a'' . As soon as the wiper A 3 reaches its fourth contact in the row I, the relay R is energized over: earth, battery, relay R, wiper A 3, contact 4 and soldering tab 4 of the side I of the intermediate distributor, jumper lead, soldering tab zv 11, earth. The relay R locks itself over the contact 33 r in the following circuit: earth, battery, relay R, contact 33 r , wiper 95 A 2, segment I of the disc A 2, earth, and at 100 the contact 32 r it opens the impulse circuit. When the wiper A 4 leaves the segment I, the steering current circuit is interrupted and the switch commences its non-numerical selection. At the same time the wiper A 2 105 leaves its segment I and opens the locking circuit for the relay R, hence the contacts 32 r and 33 r resume their normal position. During the movement over the segment II, the relay R is operated when the wiper A 3 110 reaches the ninth contact over the following circuit: earth, battery, relay R, wiper A 3, contact 9 in the contact row II, contact 3 of the storer sp 1, earth. The above described circuit changes are then repeated for the 115 other digits.

It should be noted that in the positions 4 and 5 of the side switch, the relays An 4 and An 5 are operated in the manner already described for the relay An 3, and at their contacts 44 an 4 and 45 an 5 these relays lock themselves over the wiper A 1. Relay An 4 at its contact 34 and 4 closes the gap between the segments "I-II" and "III" of the disc A 6, and the relay An 5 at its contact 35 an 5 120 closes the gap between the segments "III" and "IV-V". It has already been mentioned that the gaps between the segments are not large so that they can be bridged by the wiper, hence the coupling magnet K re- 125 130

mains energized during the entire rotation of the wiper until the release of the impulse sender. At the end of a complete rotation of the impulse sender the wiper A 1 leaves its disc, and this causes the relays An 3, An 4, An 5 to fall back. At this moment the wiper A 6 leaves its segment "IV-V". The coupling magnet K is deenergized when the relay An 3 falls back and opens the contact 27 an 3, hence 5 upon reaching its normal position, the impulse sender remains therein. The wiper A 1 also opens the locking circuit of the relay Td, which falls back and so closes the circuit of the relay F over: earth, contact 9 pd, contact 10 37 td, contact 36 g, relay F, battery, earth. Relay F operates and locks itself over: earth, battery, relay F, contact 38 f, contact 4 c, earth. At the contact 5 f the circuit for moving on the sender selector is opened, and at 15 the contact 8 f the test circuit of the sender selector is opened. Hence the latter remains at rest until the end of the connection. On falling back, the relay TD at its contacts 38 td and 39 td switches through the speaking 20 leads, thereby setting up the speech connection. After a little while the slow acting relay G falls back. After the release magnet MS has been deenergized the impulse storer SP and the impulse sender Z are ready to be 25 again taken into use.

Release

In order to release the switches, the calling subscriber hangs up his receiver, thereby de- 35 energizing the relay A. At the contact 11 a, the relay V is deenergized and after the slow acting relay V has fallen back and relay U, being momentarily energized, has fallen back, the contact 39 v closes the circuit of the re- 40 lease magnet M over: earth, contact 14 a, contact 39 v, contact 46 u, off normal contact 13 k, release magnet M, battery, earth. At contact 1 m the release magnet momentarily opens the c lead going to the second pre- 45 selector, hence the preselectors are released in known manner and the relay C can fall back. The outgoing c' lead is interrupted at the contact 3 c, thereby initiating the release of the succeeding switches. The relay F is de- 50 energized at the contact 4 c, this renders the sender selector DD ready to be again taken into use.

Exceptional operations

55 The subscriber makes a pause between the positioning of the second and third storer. The side switch goes into its position 3 after the storer sp 2 has been positioned, thereupon the relay An 3 is energized and the im- 60 pulse sender is started up. The impulse sender rotates until the wiper A 6 leaves the segment "I-II", and it then stops because the contact 34 an 4 has not yet been closed and the coupling magnet therefore is deenergized. 65 If in the mean time the subscriber has po-

sitioned the storer sp 3, the side switch goes into the position 4 and energizes the relay An 4, hence the segment III of the disc A 6 is earthed over the contact 34 an 4, the coupling magnet is then operated and causes the impulse sender to move on again. In a similar manner the impulse sender awaits the positioning of the fourth storer. 70

No further impulses are to be transmitted if the calling subscriber prematurely hangs up his receiver, the object being to prevent a subscriber being called when there is no calling subscriber at the other end. It will be assumed that the calling subscriber hangs up his receiver after he has positioned the first two storers, hence the relay C is deenergized as already described when the first group selector is released. Thereby the relay P is deenergized at the contact 3 c, and it opens the contacts 23 p, 24 p, hence no further impulses can be transmitted over the lead. At the contact 40 c the relay N is energized over: earth, battery, relay N, contact 41 td, contact 40 c, earth. At its contact 2 n, the relay opens the incoming c lead, hence the first group selector cannot be taken into use before the relay N has been again deenergized. Relay N, by closing the contact 43 n, connects a resistance over contact 42 td in parallel with the release magnet MS. Although the impulse sender remains guarded (relay Pd remains energized), nevertheless, the release magnet MS is shunted to such an extent, that it releases and in known manner causes the side switch ST to move onwards 100 into its normal position. During the onward movement into this position, the relays An 4, An 5, which have not yet been energized, are energized, hence the coupling magnet K ensures a complete rotation of the impulse 105 sender. On reaching its normal position the wiper A 1 leaves its disc, and the relay Td falls back, whereupon the relay F is momentarily energized in the following circuit until the relay G falls back: earth, contact 110 9 pd, contact 37 td, contact 36 g, relay F, battery, earth. The relay F, at its contact 8 f, opens the circuit of the relay Pd. At contact 41 td the relay N is deenergized, so that all parts are now returned to their normal 115 position.

If the calling subscriber has selected the first number and then hangs up his receiver, an impulse is sent to the impulse storing device of the impulse sender when the subscriber hangs up. The relay Q is thereby energized and is then deenergized, hence the side switch reaches the position 2. After the release of the relay V, the release magnet is energized when the slow acting relay U 120 has fallen back and has closed the following release circuit: earth, contact 14 a, contact 39 v, contact 46 u, off normal contact 13 k, release magnet M, battery, earth. The operation of the release magnet M causes the 125 130

release of the switches in the manner described above. The slow acting relay Q has sufficient time to fall back, because it can do so in the total time taken for the slow acting relay U to fall back, for the delayed operation of the release magnet M and for the release of the switch (IGW). After the release of the group selector, the relay Q receives another impulse over the following 10 circuit: earth, battery, motor magnet DSp 2, side switch arm st 1 position 2, relay Q, sender selector arm dd 3, contact 49 p, off normal contact 48 k, contact 47 m, earth. This circuit is immediately opened again, and 15 the side switch reaches the position 3. The impulse sender is started up and makes a complete rotation. Relay Td is operated. All the operations for releasing the returning to normal are effected in the manner al- 20 ready described.

If the number of digits in the calling number is not to be altered during translation, then the impulse transmission by the segment I of the disc A 5 must be suppressed. 25 To do so, the key Ta at the intermediate distributor is actuated, thereby earthing the contact VI of the disc A 3. Hence the relay R is energized already when the wiper A 3 passes over the contact VI, the circuit ex- 30 tending over: earth, key Ta, contact VI, wiper A 3, relay R, battery, earth. At contact 32 r earth is disconnected from the disc A 5, hence the impulse transmission of the row I is suppressed.

35 If the impulse storer is to be connected up at a later stage than that described in the drawing, there is no need to make any changes in the operations of the sender selector and storer. It is only necessary to 40 alter the circuit of the group selector in the drawing. The impulse bridge for example receives the following impulse transmission from the repeater at the feeding bridge of the calling station; positive impulses over 45 the a lead for positioning the switches and the application of battery to the b lead for steering them. The release has to be made dependent on the C relay at the incoming c lead. Such circuits are known. Hence it 50 is possible to insert the same sender selector and impulse sender at any desired point in the building up of a connection.

The impulse storer can also be associated with the first group selector although more 55 than one train of impulses are used for directly positioning the switches by the calling party. For example, a side switch or different relays could be so operated by a certain number of trains of impulses, that the im- 60 pulse storer can be operated only after these impulses have been transmitted.

Fig. 3 shows a modification of the circuit shown in the Fig. 1. In this circuit the sender selector does not hunt for an impulse 65 storer until the commencement of the nu-

merical selection, which serves to position the first group selector. A relay S has to be added; its circuit is prepared at the contact 4 c' when the first group selector is taken into use, and it is closed as follows when the re- 70 lay U' is operated at the commencement of the impulse transmission: earth, contact 4 c', contact u', relay S, battery, earth. Relay S is operated, it locks itself over contact 1 s, and starts up the sender selector DD' by 75 closing the motor magnet circuit at 2 s over: earth, contact 2 s, contact 5 f', contact 6 pd', rotary magnet Dd', contact 7 dd', battery, earth. Thus the contacts 2 s and 3 s take over the functions of the contacts 4 c and 40 c in 80 the Fig. 1. All the other functions remain the same as in Fig. 1.

What is claimed is:

1. In a telephone system, a trunk line, an automatic switch terminating said trunk line, a plurality of registers, switching mechanism for associating an idle register with said trunk line, means for sending series of impulses over said trunk line, means for operating said switch responsive to one series of impulses sent over said trunk line, means responsive to the commencement of the operation of said automatic switch for operating said switching mechanism to associate an idle register with said trunk line, and means for rendering said register effective to register other series of impulses sent over said trunk line. 90

2. In a telephone system, a trunk line, a train of automatic switches, a register sender, switching mechanism for associating said register sender with said trunk line, means for sending impulses over said trunk line, means for operating one of said automatic switches in said train directly responsive to impulses sent over said trunk line, means for operating said switching mechanism, means for rendering said register sender effective to register other impulses sent over said trunk line, the operation of said other switches in said train being then controlled by impulses sent over said trunk line by said register sender, and a line relay for controlling the operation of said one of said automatic switches and said register sender. 105

3. In a telephone system, a trunk line, a train of automatic switches, a register sender temporarily associated with said trunk line for registering and retransmitting current impulses, said register sender being normally ineffective, means for sending a plurality of series of impulses over said trunk line, means responsive to one series of impulses for operating one of said switches, means responsive to said operation for rendering said register sender effective to register the other series of impulses, and means in said register sender for transmitting a different number of series and a different number of 110 115 120 125 130

impulses in each series, to operate the other switches in said train.

4. In a telephone system, an automatic switch, a relay in said switch, a register sender associated with said switch, an impulsive circuit including contacts on said relay for operating said switch, and an impulsive circuit including other contacts on said relay for the positioning magnets of said 70 register sender.

5. In a telephone system, a trunk line, an automatic switch terminating said trunk line, registers, means for sending series of impulses over said trunk line, means for 80 directly operating said switch responsive to and in accordance with one series of impulses sent over said trunk line, switching mechanism for associating an idle register with said trunk line, means responsive to the commencement of the sending of said one 85 series for starting the operation of said switching mechanism, and means for rendering the associated register effective to register other series of impulses sent over said trunk line.

6. In a telephone system, a trunk line extending to an automatic switch, means for operating said switch responsive to a series of directive impulses transmitted over said 90 trunk line to extend a connection towards a called line, a group of registers, and means responsive to the first impulse of said series for selecting an idle register and connecting it to said trunk line.

35 7. In a telephone system, a trunk line, means for sending impulses over said trunk line, a register normally disconnected from said trunk line, and means responsive to the first impulse of one series of impulses sent 95 over said trunk line for connecting said register to said trunk line.

8. In a telephone system, a trunk line, an automatic switch, means for sending impulses over said trunk line, a second trunk line, means responsive to certain impulses 100 for directly operating said switch to connect the first trunk line with the second trunk providing the second trunk line is idle, a register sender for registering other impulses regardless of whether or not the first trunk line has been connected with said second trunk line, and other switches controlled by said register sender to extend said second trunk line to a called line providing 110 said first trunk line is connected to said second trunk line.

60 9. In a telephone system, a train of directive automatic switches for extending a connection from a calling line to a called line, register senders, means controlled by the calling subscriber for directly operating the first switch of the train in accordance with the first digit of the called number to connect with the second switch of the 120 train, means effective while the switch is

being operated to select an idle register sender, means for then registering the remaining digits of the called number on the selected register sender, and means for thereafter operating the remaining switches 70 in said train under the control of said register sender.

In witness whereof, I hereunto subscribe my name this 18th day of March, A. D. 1926.

FRITZ LUBBERGER.
